UNITED STATES PATENT OFFICE.

HUGO TUECKMANTEL, OF NEWARK, NEW JERSEY.

BAG FRAME.

Application filed December 14, 1922. Serial No. 606,785.

To all whom it may concern:

Be it known that I, HUGO TUECKMANTEL, a citizen of the United States, residing at Newark, in the county of Essex and State 5 of New Jersey, have invented new and useful Improvements in Bag Frames, of which the following is a specification.

This invention relates to improvements in bag structures as used by travellers in containing and conveying miscellaneous articles in a convenient and secure manner.

The principal purpose of the invention is to produce a disappearing folding frame, wholly and completely obscured when the 15 bag is closed and which holds the bag fully open when distended.

Another object is to provide a bag frame that, when covered and assembled in the bag, blends into its contour in a particularly 20 graceful and harmonious manner, the frame elements being substantially indistinguishable from the bag covering.

A further aim is in the provision of a novel type of bag frame, possessing rigidity 25 and strength combined with simplicity and lightness, which can be economically constructed and assembled to present an exceptionally neat and attractive structure.

These and other like aims, objects and 30 purposes, which will become apparent as the description proceeds, are attained by the novel construction, combination and arrangement of parts, hereinafter described and shown in the accompanying drawings, 35 forming a material part of this disclosure, and in which:—

Figure 1 is a perspective view of a bag made in accordance with the invention, the same being shown in a closed position.

40 Figure 2 is a similar view of the same, looking from the opposite side of the bag when in an open position.

Figure 3 is a fragmentary perspective view of the bag frame looking from its 45 lower or inner side when distended or open.

Figure 4 is an enlarged transverse sectional view taken on line 4—4 of Figure 3, as covered with the bag material.

Figure 5 is a similar sectional view taken 50 on line 5—5 of Figure 3.

Figure 6 is a transverse sectional view taken through the frame elements when folded and prior to covering.

55 A conventional type of bag is shown in Figures 1 and 2, the same resembling the well known Gladstone pattern, and being

comprised of side and end walls, respectively 15 and 16, having between them a bottom and being lined as at 17 and 18, the structure being of the usual rectangular 60 shape, provided with welted seamed edges and reenforced lower corners.

A handle 19 is provided on one side frame member, below which is a lock 20 and slide bolts 21 near the ends are adapted to engage with mating elements 22 on the other, opposite frame member, which is further provided with a pull 23 as shown, these parts being of the usual construction.

The invention resides in the frame, best 70 shown in assembled relation, clear of the bag material, in Figure 3 and particularly in the manner of attaching the side and end walls as hereafter explained.

One of these frame members 24 consists 75 of a flat metallic strip of uniform width, equal in length to the interior of the bag and provided with suitable openings (not shown) for engaging the handle, lock and slide bolts.

A second strip 25, relatively narrower and corresponding in length with the first, is disposed at a right angle therewith, there being an intervening space 26, said strips being held in rigid relation by a plurality 85 of angularly bent clips 27 riveted respectively to the underside of the strip 24 and outer side of strip 25, passing through the space as shown.

The opposite frame member consists of a 90 like strip 28, approximately one-third the width of the corresponding element 24.

At a right angle to the element 28 is another strip 30, opposite the element 25 and having an outturned longitudinal flange 31 95 for reenforcing purposes, the strips 28 and 30, like the preceding pair being held in rigid relation by clips 32 passing through the intervening space 33 and are similar in shape and disposition to the clips 27, the outermost pairs of clips being at the extreme ends of the frame members.

Securely fixed to the inner adjacent surfaces of the elements 25 and 30, at their ends, are forked brackets 34 carrying pivots 35 on which are mounted, between the forks, the outer ends of pairs of channel shaped end elements 36 and 37 of equal length, each pair being connected by a hinge joint 38 which permits folding in one direction to close the frame, but resists pressure in the opposite direction, permitting 105 110

these elements to be extended at right angles to the side members only, or to fold closely adjacent when closed, to completely disappear, being concealed within the walls of 5 the bag, the length of the paired end elements controlling the width of the bag opening.

Said end elements are completely enveloped by the bag material as shown in 10 Figure 2, the lining being entered between the lap of the material and secured by a row of stitches 39.

The wider side frame member, as shown in Figure 5, has its several elements enveloped in a separate covering 40 held by a 15 row of stitches 41 passing through the space 26 and the edges 42 of the covering are received between the material of the bag wall 15 and its lining 17, being confined by a row 20 of stitches 43, thus forming a neat and secure joint at which no metal appears or offset element of any kind.

In a similar manner the opposite frame member is enveloped in a covering 44 25 stitched through the space 33, by the seam 45, its ends 46 being held between the bag wall and lining by the row of stitches 47.

It is to be understood that the axes on 30 which the side frames turn are separate and horizontal, being at variable heights along the vertical side walls of the bag and not in a median plane therebetween as is customary in common types of like bags.

From the foregoing it will be seen that a 35 strong bag of particularly pleasing appearance has been produced and in which the folding frame is wholly and completely obscured when the bag is in a closed position, the walls of the bag blending smoothly with 40 the covering of the frame elements so that the same are practically indistinguishable.

While certain preferred embodiments of this device have been shown and described, it will be understood that changes may be

made in its construction, without the exercise of invention, or conflicting with the scope of the claims hereto appended.

Having thus described my invention, what I claim as new and desire to secure by Letters Patent, is:—

1. A hand bag comprising the combination with a flexible bag body capable of being fully opened at the top, and a folding frame wholly contained within the bag body near the edges of the side and end walls adjacent the top, said frame consisting of toggle elements at the ends thereof, and side members each constructed of two elements placed at an angle with each other, said last mentioned elements being spaced from and attached to each other, the flexible bag body being secured adjacent said space. 60

2. A hand bag comprising the combination with a flexible bag body capable of being fully opened at the top, and a folding frame wholly contained within the bag body near the edges of the side and end walls adjacent the top, said frame consisting of toggle elements at the ends thereof, and side members each constructed of two elements 70 placed at an angle with each other, said last mentioned elements being spaced from and attached to each other, said toggle elements secured to the side members below the space.

3. A hand bag frame consisting of toggle 75 elements at the ends thereof, and side members each constructed of two elements placed at an angle with each other, said last mentioned elements being spaced from and attached to each other, said toggle elements 80 secured to the side members below the space.

This specification signed and witnessed this 13th day of December, 1922.

HUGO TUECKMANTEL.
